UNITED STATES PATENT OFFICE.

MICHAEL J. BANKS, OF BILOXI, MISSISSIPPI

HYDROCARBON BURNER.

Application filed January 6, 1925. Serial No. 865.

This invention relates to a hydrocarbon burner adapted to be received in the fire box of stoves, furnaces, or the like for heating the same, and aims to provide a novel and improved device for vaporizing liquid fuel, such as kerosene, crude oil, etc. prior to the ignition thereof, so as to insure complete combustion and hence an economy in the consumption of fuel, which will minimize the deposit of carbon that tends to reduce the efficiency of a device of this character.

Another object of the invention is to provide a gas generating chamber arranged above a burner, said chamber being so constructed that the flames from the burner will pass therethrough in order to cause the complete vaporization of the hydrocarbon liquid passing therethrough to the burner.

It is also another object of the invention to provide a hydrocarbon burner of the kind indicated, which is simple and substantial in construction; which can be manufactured economically; and which will be thoroughly efficient and practical in use.

With the foregoing and other objects in view, which will be apparent as the description proceeds, the invention resides in the construction and arrangement of parts, as hereinafter described and claimed; it being understood that changes can be made within the scope of what is claimed without departing from the spirit of the invention.

The invention is illustrative in the accompanying drawings, wherein:

Figure 1 is a side elevation of my improved device, showing a pair of burners arranged for use, one thereof being shown in section;

Figure 2 is a plan view thereof taken on line 2-2 of Figure 1;

Figure 3 is an end elevation of the same;

Figure 4 is a section on line 4-4 of Figure 3;

Figure 5 is a section taken on line 5-5 of Figure 2;

Figure 6 is a plan view of a modified form of my invention, showing but one burner used, and

Figure 7 is a still further modified form of the invention, showing a pair of burners arranged side by side.

Referring to the form of my invention illustrated in Figures 1 to 5 inclusive, a pair of hydrocarbon burners generally indicated by the letter B, is shown. Said burners are adapted to be carried by an elongated pan

or plate 10 having an upturned flange 11 extending around the outer marginal edge thereof. At each end of the pan 10 is provided a supporting member 12 adapted to be secured to the pan or plate 10 for holding the same in an elevated position, each of said supporting members consisting of a pair of upwardly directed arms 13 each having a slot 14 therein through which extends a bolt 15 for attaching said arms to the pan or plate, said supporting members also having their lower ends flanged outwardly at right angles to provide base plates 16 for engaging a grate or other element in a fire box in order to properly support the device. By the provision of the slots 14 in the arms 13 it will be noted that the pan or plate 10 may be adjusted to the desired height.

At each end of the pan or plate 10 an opening 17 is provided for receiving the lower ends of pipes 18, each of said pipes adapted to be secured in said openings by a pair of binding nuts 19 threaded on said pipes and arranged on the opposite sides of the pan or plate 10. Attached to the pipes 18 adjacent the lower binding nuts 19 are coupling members 20 having their lower ends reduced in size for receiving and retaining the outwardly flared ends 21 of the tubes 22.

The tubes 22 extend towards each other as they extend away from the pan 10 and have attached to such extending ends valves 23 which in turn are attached to a pipe 24 by means of T connection members 25. The pipe 24 has one end thereof secured to a liquid fuel supply pipe 26 leading from the main fuel reservoir (not shown), while the opposite end of said pipe 24 is closed by a closure cap 27 attached to one of the T-shaped connection members 25. The pipe 24, T members 25, and valves 23 are arranged to be carried by a plate or door 28 of the stove or furnace in which the burners are mounted. By the provision of the valves 23 the flow of liquid fuel from the fuel supplying tube 26 to the pipes 18 can be regulated.

The upper ends of the pipes 18 are turned inwardly at right angles, as at 29, and are threaded or otherwise attached to one end of the gas generating members 30, which consists of a rectangular block having cylindrical passageways formed therein conforming to the general rectangular shape of the

block, that is, the passageways have parallel side portions 31 extending lengthwise of the block, for communicating at their opposite ends with cross portions 32 arranged 5 at the opposite ends of the block. The various passageways may be formed by drilling into the blocks from various sides thereof and closing the outer ends of said drilled portions with threaded plugs, as indicated 10 by the numeral 34.

The pipes 18 are attached to the blocks or gas generating members and are in communication with one of the cross passageways 32 intermediate said passageway's 15 ends, while pipes 35 are attached in a like manner in communication with the other cross passageway at the opposite ends of each block. The pipes 35 are bent in U-shaped form, with the lower ends 36 thereof 20 extending under the blocks 30 and are adapted to be supported by angle brackets 37 attached to the pan 10. On the upper sides of each of the portions 36 of the pipes 35 are provided a pair of orifices 38 from which 25 flames or adapted to be projected, while on the outer ends of said portions 36 are attached closure caps 39.

Arranged directly above the orifices 38 are the blocks or gas generating members 30 which have provided in the central portions thereof between the passageways therein in a plurality of openings 40 extending entirely therethrough and being slightly reduced in size as they extend upwardly 35 through the blocks, in order to provide vertical, tapered apertures for permitting the flames projected from the orifices 38 to pass through the blocks, thus thoroughly heating the same and consequently causing the complete vaporization of the liquid fuel passing 40 through the passageways 32 and 33 in the blocks.

Directly below the portions 36 of the pipes 35 the pan 10 is slightly depressed to form 45 receptacles 41 for receiving asbestos wicks 42. At each side of the receptacles 41 an elongated opening 43 is provided to permit air to pass upwardly through the pan or plate. Said openings 43 have upturned 50 flanges 44 extending entirely around the same for preventing hydrocarbon liquid deposited on the pan or plate from passing through said openings 43. Between the two burners B and at each corner of the pan or 55 plate 10 are provided additional openings having like flanges for a like purpose, the opening between said burners being designated by the numeral 45, while the ones in the corners of the pan or plate are indicated 60 by the numeral 46.

In order to render my device more efficient and practical in use, the blocks or gas generating members 30 and the pipes 18 and 35 are constructed of brass material, as I have 65 found that brass is an excellent heat con-

ductor as well as a material that will minimize the carbonization of the fuel while passing through said members.

In Figure 6 I have illustrated a one burner apparatus. Such a device could be 70 used where the compartment in which the apparatus is to be placed is rather small, as well as in places where less heat is desired.

A further modified form of the invention 75 is shown in Figure 7. This form shows a pair of burners utilized as in the main form of my invention, but the burners are arranged side by side instead of to the ends of each other. By such construction the 80 apparatus is reduced in size and is in a form that will render it adaptable to different shaped fire boxes.

In operation, the valves 23 are opened 85 until a few drops of hydrocarbon liquid fuel are deposited on the asbestos wicks 42. The valves 23 are then closed and the liquid fuel on said wicks ignited, which will heat the gas generating members and the portions 36 of the pipes 35, thus vaporizing the liquid 90 fuel contained therein. As soon as gas is generated, the valves 23 are again opened, and by turning said valves the flames from the orifices 38 can be regulated. When the gas generating members are thoroughly 95 heated, the liquid fuel entering same will be completely vaporized before the same enters the pipe 35 to pass to the orifices 38.

Having thus described my invention, what I claim as new is:

1. A hydrocarbon burner comprising a gas generating member constructed in block shaped formation so as to retain heat, said block shaped gas generating member having a passageway formed therein, a feed pipe 105 attached to said gas generating block member and in communication with the passageway therein, a burner pipe also attached to said gas generating member and in communication with the passageway, said burner pipe extended beneath said gas generating block member for heating the same, said block shaped heat retaining gas generating member having a series of small vertical openings extending therethrough for permitting flames from said gas pipe to pass 110 therethrough to heat the same.

2. A hydrocarbon burner comprising a base pan, feed and burner pipes supported by said pan, a gas generating member having passageways arranged therein, said gas generating member having one end attached to said feed pipe with the passageways therein, in communication with said feed pipe while the opposite end thereof is attached to the burner pipe which is also in communication with the passageways, said burner pipe adapted to extend beneath said gas generating member for heating the same, said gas generating member having a series 120 125 130

of relatively small vertical openings arranged therein for permitting the flames from said burner pipe to pass therethrough.

3. A hydrocarbon burner comprising a base pan, feed and burner pipes supported by said pan, a gas generating member having passageways arranged therein, said gas generating member having one end attached to said feed pipe with the passageways therein in communication with said feed pipe while the opposite end thereof is attached to the burner pipe which is also in

communication with the passageways, said burner pipe adapted to extend beneath said gas generating member for heating the same, ¹⁵ said gas generating member having vertical openings arranged therein which are slightly tapered inwardly as they extend upwardly through the same for permitting the flames from said burner pipe to pass therethrough. ²⁰

In testimony whereof, I have affixed my signature.

MICHAEL J. BANKS.
